Application September 24, 1936, Serial No. 102,261
In Great Britain October 9, 1935

6 Claims. (Cl. 197—133)

The present invention relates to fan fold billing devices for typewriters and is concerned with means applicable thereto to enable the use therein of continuous or fan fold stationery, that is, long continuous strips of paper interleaved with short strips of carbon paper intended for the production of sets of manifold copies of forms, such as accounts, statements, invoices, each set comprising a top typewritten ribbon copy and a plurality of carbon copies. The means above referred to is designed to be particularly applicable to high speed power-operated typewriters in which every movement in the production of finished invoices, statements, and the like, take place in the minimum possible time.

An important requirement in a typewriter intended for use with continuous or fan fold stationery is that the platen may be easily and quickly raised from typing position to a position in which the fan fold or continuous stationery, including carbon sheets, lying therebeneath can be freely moved, adjusted, and arranged, for example, to strip the carbon sheet from a finished form, and that the platen may be equally quickly and easily lowered from its elevated position to typing position in which position it shall be adequately locked against unwanted movement.

In accordance with the present invention there is provided for use with a typewriter a platen raising device comprising an upward extension at each end of the typewriter carriage, means for permitting the platen to be slid substantially vertically between said extensions, and means for releasably maintaining the platen in a raised or non-typing position. Further, in accordance with the invention, a paper bail is provided adapted to bear resiliently against the platen when the latter is in typing position. There is provided a fan fold or continuous stationery supporting device comprising a supporting table mounted for transverse movement upon rails or the like and provided with means by which said device is attached to the typewriter carriage in a resilient manner. Other features of the invention will be explained hereinafter in the general description.

In order that the present invention may be more fully understood and readily carried into effect, one embodiment of the same will now be described with reference to the accompanying drawings, in which:—

Figure 1 is a side-elevational view of a typewriter having the platen raising and continuous stationery supporting devices of the present invention applied thereto;

Figure 2 is a plan view of the apparatus shown in Figure 1;

Figure 3 is a side-elevational view, to a larger scale, of the platen raising mechanism appearing in Figure 1, with the platen in its raised or non-typing position;

Figure 4 is a view similar to Figure 3, but showing the platen in its lower or typing position;

Figure 5 is a front elevation of the platen raising mechanism.

Figure 6 is a large scale view of certain parts shown in Fig. 1.

Figure 7 is a large scale vertical section showing the construction of the carbon strip holder;

Figure 8 is a large scale plan view of one end of the carbon strip holder.

The drawings show how the present invention is attached to the well known "International" power operated typewriter, formerly known as the "Electromatic," but the invention may easily be used with other typewriters as well as with the one shown, whether they be manually or power operated.

Referring now to Figures 1 and 2 of the drawings, the typewriter 1, of which only the rear portion is seen in the drawings, is mounted upon a base which consists of two sheet metal base strips 2 integrally joined by an angle strip 2a which extends parallel with the rear part of the base of the typewriter. The strips 2 and angle strip 2a serve as a foundation for the stationery supporting device to be more fully described hereinafter. The typewriter is provided with platen raising means which also will be fully described hereinafter, the platen being designated 3 and 35 its usual operating knobs 4.

At the rear of the typewriter carriage 5 there is provided a rod 6 parallel with the platen roller 3, said rod 6 being held removably at each end in extension 7 of plates 34 secured to the typewriter carriage side frames 8. Any suitable means such as a cotter pin 9, (see Fig. 6 also), is utilized to prevent rod 6 from being accidentally displaced longitudinally of the extension 7. A pair of plates 10, 11 attached to the main framework of the stationery supporting device (generally designated 12), are provided with slots of a diameter slightly greater than that of rod 6, and when the stationery supporting device is to be operatively connected with typewriter 1, rod 6 is passed through the slots in each of lugs 10, 11 and secured in extensions 7. Between the respective plates 10, 11 and suitable stops or collars 13, 14, adjustably secured on rod 6, there are provided coil springs 15, 16, the springs 15, 16

55

- being so arranged on rod 6 that they lie on the outer sides of plates 10, 11, and so oppose each other. It will thus be appreciated that if the typewriter carriage 5 is now moved on its supporting rails, as occurs when the typewriter is operated in a normal manner, such movement will be communicated to the stationery supporting device 12, through the resilient agency of springs 15, 16.
- 10 The main framework of device 12 consists of two side plates 12a having the general shape of inverted bridge trusses rigidly joined by a central stiffening plate 12b and braced horizontally by two diagonal intersection braces 12c secured to the 15 upper front corners (Fig. 1) of the side plates and to the portion of side plates 12a adjacent the lower corners of plate 12b. A front plate or plates 12d rigidly joins the front ends of plates 12a while a horizontal plate 12e joins the upper 20 rear edges of the plates 12a.

The rail 17 consists of a bar mounted behind the typewriter carriage 5, parallel with the platen, by means such as diagonal braces 17a and 17b, secured to the ends of rail 17 and to 25 the ends of angle strip 2a, and to rail 18, respectively. This leaves a clear space between angle strip 2a and rail 17 for the plates 10, 11 and certain other parts at the front of device 12 to travel with the carriage without interference. 30 If desired, a suitable plate can be substituted for the diagonal braces 17a and be provided with a long rectangular opening to permit the lugs 10, 11 and parts of the device 12 above and below said lugs to move with the carriage without 35 interference.

Two pairs of rollers 20 are mounted on studs carried by the front plate 12d joining the sides of device 12 at the front ends thereof. These 40 rollers engage the top and bottom faces of rail 17 and support and guide the front end of device 12 for free movement with the typewriter carriage 5. In order that the device 12 shall be capable of movement along rail 17 without whip or play, two further sets of rollers 21, 22 are provided, engaging the rear and front surfaces, respectively, rail 17, rollers 21, 22 being 45 mounted on brackets 23, 24 rigidly secured to or forming part of the plate 12d on the front end of device 12. The track 18 consists of an angle strip secured to the rear ends of the base strips 2 and supports the bulk of the weight of the main framework of device 12 by means of a flanged roller 18a carried by a stud mounted on the central, stiffening plate 12b joining the 50 sides of the device 12. The main framework of device 12 is thus adapted to move transversely upon rails 17, 18 with every movement of the typewriter carriage.

Upon the upper surface of the main framework 60 of device 12 is carbon sheet stripper carriage generally designated 23a upon which a carbon-strip holder 27 is mounted for longitudinal sliding movement. This carriage consists of a substantially flat plate having its front and 65 rear edges rolled as at 23b to provide a smooth paper guiding surface and to stiffen the plate transversely of the main framework of device 12. Plate 23a is also provided with longitudinal stiffening ribs 23c. The entire carriage 23a is 70 freely slideable longitudinally of the main framework of device 12 (at right angles to the axis of platen 3) being provided with rollers 26a engaging the edges of angle strips 24b secured to the top edges of plates 12a. The longitudinal 75 movements of carbon carriage 23a are effected

by a handle 26 which projects forwardly from plate 23a to a point just behind the platen 3 of typewriter 1.

The carbon strip holder 27 consists of a bar having a lug 27a (Figs. 7 and 8) at each end 5 bent longitudinally of the bar so as to make an angle of approximately 45° with the plane of the bar. A pair of pins 28, 29 are secured to each lug for the purpose of removably mounting the carbon strip anchoring blades 30. Loops 31 10 (Fig. 7), formed in a well known way in the carbon sheets or strips 32, are slipped over the blades 30 (Fig. 7) to anchor the carbon strips in the holder 27. Each blade 30 is provided at one end with two holes adapted to register with one pair of the two pairs of pins 28, 29, and only the perforated portion of each blade 30 extends beyond the carbon strip for the purpose of mounting it on these pins. The blades 30 are placed alternately upon the pairs of pins 28, 29 15 as shown in Figs. 2 and 8, and separated by spacing collars 30a so that each blade extends part way between an opposed pair of blades mounted on the opposite pair of pins and supports its carbon sheet 32 therebetween. The 20 blades are clamped in place on pins 28, 29 by means of thumb-screws 28a, 29b. The perforated portion of each blade 30 is twisted at an angle of approximately 45° to the plate of the rest of the strip so that when the blades are 25 in place on pins 28, 29, although the latter are, as shown, oblique (at an angle of approximately 45° to the horizontal), the carbon-sheet-supporting portion of each blade 30 is parallel with the plane of carriage 23. The effect of the obliquity of pins 28, 29, however, is to cause blades 30 to lie parallel with each other, but in echelon formation when viewed in cross-section as in Fig. 7. This arrangement enables coincident transverse creases 33a in a plurality of superposed sheets or webs 33, each passing between an adjacent pair of blades 30 and hence between an adjacent pair of carbon sheets extending forwardly towards the typewriter 1 from said blades, to reach the blades 30 sequentially and not simultaneously. In this way the frictional gripping or binding effect, which is experienced when transversely creased stationery is drawn through the carbon-anchoring blades 30, is reduced by being spread over a period of time instead of being encountered at one point only, and does not become so great at any instant as to cause unwanted binding between the carbon sheets 32 and the paper sheets or webs 33. 40

As is usual in using continuous or fan fold 55 billing machines of the type shown, only a small portion of each carbon sheet is used in typing each form and the worn portions are torn off from time to time as the transfer material on the used portions becomes exhausted. After 60 tearing off the worn portions, the carbon sheets must be relocated before a new series of forms can be typed to compensate for the portions torn off. In order to permit this relocation of the sheets with a minimum of time and effort 65 means is provided for moving the carbon sheet holder 27 forwardly in proportion to the length of carbon sheet removed. The plate 23a is provided with notches 23d along its longitudinal edges with the notches of one row in alignment 70 with those of the other row. One end of bar 27 has a detent block 27b (Fig. 8) and a plate 27c secured thereto, block 27b having a tooth engaging a notch in plate 23a, while plate 27c loosely projects under plate 23a to prevent lifting bar 75

27. The opposite end of bar 27 has a similar but somewhat wider detent block 27d (Fig. 7) having a tooth engaging the notch opposite the one engaged by the detent block 27b. The detent block 27d is associated with a leaf spring 27e instead of a plate like 27c and the leaf spring is bent downwardly away from detent block 27d and horizontally along bar 27 underneath plate 23a so as to bear on the adjacent rib 23c, as shown in Figs. 2 and 7. When it is desired to relocate the carbon strip holder, the end of bar 27 having the leaf spring is raised against the tension of the spring until the tooth in detent block 27d clears its notch. The bar 27 is then pushed longitudinally to disengage the tooth in the detent block 27b from its notch, leaf spring 27e being so shaped as to permit this last movement. Bar 27 is now moved longitudinally at both ends the approximately desired amount and relocked in place by reversing the procedure just described to relocate the teeth in the detent blocks in the notches nearest the desired position.

15 The movements of carriage 23a during carbon stripping operations are limited by means of an adjustable stop 60 consisting of a finger mounted on a rod 61 and to the rod secured by a setscrew. Rod 61 is mounted in a hole in the upper edge of plate 12b and in a hole in a block 62 secured to rod 63 which is mounted on plates 12a. Finger 60 engages the rear end of the 20 carriage 23a during the carbon stripping operation and by adjusting the finger longitudinally of the rod 61, the device 12 is accommodated to typing on forms of different lengths.

25 The continuous or fan fold stationery is supported at the rear of the device 12 by a bar 64 secured to the angle strips 24b and curving in transverse section to provide a smooth guiding surface. Side guides are provided consisting 30 of hubs 65 to which are secured guides 66, each comprising a strip bent upwardly (Fig. 2), outwardly away from the longitudinal axis of device 12, upwardly, and then back inwardly a short distance toward said axis by right angle 35 bends. Similar guides 66 are provided at the front end of device 12 and are mounted on a rod 68. The side guides are secured by means of suitable set screws or thumb screws in the hubs and guide the edges of the superposed 40 sheets or webs of continuous or fan fold stationery.

45 Turning now to Figures 3 and 4 of the drawings, which illustrate respectively the raised and lowered positions of the platen raising device 50 of the present invention, and also to Figure 5 which is a front elevation with the platen in typing position, it will be seen that the side plates 34 consist of a vertical sheet metal plate formed with a vertical slot 35, and rigidly joined 55 together at the top by a rod 34a. Adjacent each slot 35 there can ride a frame member 36, guided therein by flanged rollers 36a, and it is in holes in the lower ends of a pair of frame members 36 that the shaft of platen 3 is mounted 60 ed, instead of being journaled in the typewriter carriage itself as is normally the case. A toggle 65 consisting of two toggle links 37, 38 connects each of frame members 36 with a shaft 41 journaled in the upper ends of side plates 34, and 70 each toggle is substantially straight when platen 3 is in its lower or typing position (Figs. 4 and 5). If, with the platen 3 in this position the toggle 39 be "broken," as by pulling forward a handle 40 secured to the shaft 41, on which shaft 75 75 are pinned the upper links 37 of the toggles,

then frame members 36, carrying with them the platen 3 are caused to rise. This movement continues until frame members 36 reach the top of slots 35 in plates 34 as in Fig. 3. In this position of frame members 36, a catch 42, actuated by a spring 42, engages in a notch 43 (see Figs. 1, 2 and 5) formed in one of the frame members 36, whereby said members and platen 3 are held in raised position.

5 A cam finger 45 is pivoted at 46 on each side 10 plate 34 and has a bent over lug 45a extending behind the side arms of a paper bail 47. The latter is pivoted on shaft 41 and tends to rock rearwardly, or clockwise in Figs. 3 and 4 due to springs 47a anchored to the arms of said 15 bail and to pins 47b secured to rod 34a. Bail 47 extends parallel with a tearing knife 48 secured to brackets 34b carried by plates 34 above and in front of the platen. The cam fingers 45 each have a straight cam surface 45b above a 20 dwell 45c in which pin 44 rests when the platen roller is in lowered position. When the platen is raised, pins 44 move onto the cam surfaces 45b thereby rocking fingers 45 clockwise from the position of Fig. 4 to the position of Fig. 3 25 thereby causing bail 47 to move to a position close to the tearing knife 48.

When the platen is in its raised or non-typing position, fan fold or other stationery, carbons, or the like may be freely introduced and arranged beneath the platen and between side plates 34. If now a firm downward pressure be exerted on knobs 4 by the operator, the spring operated catch 42 is forced out from notch 43, and plate 3 descends into typing position, doubling the stationery below it as it does so, so that the stationery (not shown) lies around the roller 3 in typing position. When the platen 3 is lowered, the paper bail 47 is released and permitted, under tension of springs 47a, to bear 40 against the stationery so as to hold the same well away from that side of the platen 3 which is struck by the type. It is to be remarked that not only do the toggles 37, 38 straighten to the position shown in Figure 4 when platen-roller 3 45 reaches typing position, but they pass slightly beyond their straight, or true dead-centre position, and are prevented by pins 44 from being again "broken" by upward pressure on the platen alone. Thus the platen is securely locked 50 in typing position and cannot be forced upwardly by the pressure of the usual pressure rollers when a thick pack of forms with interleaved carbon sheets are present between the pressure rollers and platen.

55 A clamping bar is provided which is automatically operated and co-operates with the tearing knife 48 to hold the pack of superposed webs or sheets with the interleaved carbon sheets while the typed forms are being torn from the 60 next set of untyped forms. The clamping means consists of a pair of arms 51 secured to shaft 41 and a clamping bar 52 secured to said arms. Normally the bar 52 occupies the position of 65 Figs. 4 and 5 directly behind the tearing knife 48, above and in front of the paper bail 47, but, when the platen is raised, arms 51 and bar 52 are swung rearwardly and upwardly to the position of Fig. 3 well clear of the typed forms.

70 The complete operation of the invention will now be described briefly.

75 Either fan fold forms or separate superposed webs may be used in the machine and may be wound on rolls or arranged in zig-zag folded stacks. Assuming fan fold forms are used, the

stack or roll of forms is placed directly behind the stationery supporting device 12 and the leading edges of the first forms are drawn forwardly over the guide bar 64, and the carriage 23a, between the side guides 66, 67, which are set to loosely engage and guide the edges of the forms, and underneath the platen which is raised for this purpose. The forms are drawn forward far enough to overlie the paper bail 47 and tearing knife. The carbon blades 30 with the carbon sheets 32 anchored thereto are now inserted side-wise between the folds of the fan fold forms, beginning with the carbon sheet and blade which will normally be at the bottom of the pack, and placed alternately on the pins 28, 29, inserting the proper spacers 30a as the blades are stacked on the pins. After all the blades are stacked, the thumb screws 28a, 29a are turned tight. As each carbon sheet and blade are inserted, the carbon sheet is straightened and smoothed out so as to lie flat between the forms without wrinkling and the holder 27 is adjusted so that the leading edges of the carbon sheets extend slightly forwardly of the point in the first set of forms where the first line of typing is to be placed. The carbon sheets should fall short of the leading edges of the first set of forms by at least half an inch. Preferably the forms and interleaved carbon sheets are initially arranged so that when the platen is lowered and the forms are wrapped around the platen to the extent necessary, the previously typed forms can be torn from the next set of untyped forms. The stop 60 is now set so that it abuts the carriage to limit rearward movement and the platen is lowered, as described, by pressing down on the platen knobs 4.

As the platen descends, arms 51 and clamping bar 52 swing forwardly toward the tearing knife 48 and paper bail 47, and at the same time the forms are wrapped about the platen. Bar 52, in moving toward the tearing knife 48, pushes the leading parts of the first set of forms against said knife, also moving the paper bail 47 toward the knife against the tension of springs 47a so that the forms will be lightly held by the clamping bar 52 when the platen reaches typing position. The platen is now turned backwardly far enough to draw the leading edges of the first forms clear of the clamping bar 52, whereupon paper bail 50 47 returns to the position of Fig. 4 carrying with it the first forms. The platen is now turned forwardly far enough to bring the forms into position for typing the first line.

When the typing of each form is finished, the platen is turned forwardly far enough to bring the finished forms into position to be torn from the untyped forms, the platen is then raised, as described, by pulling forward lever 40. The clamping bar moves backwardly and upwardly to the position of Fig. 3. The operator next pulls the forms forwardly and, by grasping the leading edges of the forms, pulls them straight, so that the superposed webs with interleaved carbons lie substantially horizontal, and then, while still holding the forms, by means of handle 26, pushes the carriage 23a rearwardly against the stop 60. This causes the carbon sheets to be drawn back or "stripped" to a corresponding position with respect to the next set of forms.

70 The platen is now lowered, wrapping the forms around the platen, and bar 52 again presses the forms lightly against the tearing bar 47. The forms now occupy substantially the same position they had before the carbon sheets were stripped from the finished forms, except that the severing

line between the finished and unfinished forms now registers with the tearing edge of the knife 48 instead of being held away from the knife by the paper bail 47. The finished forms are now torn from the next set of untyped forms and the platen is then manipulated as before to clear the leading edges of the untyped forms from clamping bar 52 and bring them into position for typing the first line.

When the transfer material on the active or working portions of the carbon sheets becomes exhausted, it is desirable that the used portions of the sheets be severed from the unused portions and that the carbon strip holder 27 be moved forward on carriage 23a an extent equal to the length torn from each of the carbon sheets. It is usually more convenient to do this when a set of finished forms is severed. One simple way in which the used portions may be torn is to raise the platen after a form is completely typed, straighten out the webs, and then, by operating handle 26, move the carriage 23a rearwardly a distance equal to the length of carbon sheet to be removed. The platen may now be lowered again and the typed set of forms with the interleaved used portions of the carbon sheets torn from the next set of untyped forms and the unused portions of the carbon sheets, respectively. With the platen in typing position, the carbon holder 27 is disengaged from carriage 23a in the fashion described above and replaced on the carriage, after moving the latter backwardly relative to the carbon sheet holder 27 an extent equal to the length of the severed portion of carbon sheet. This leaves the carriage spaced away from the stop 60 an extent equal to the amount the leading edges of the carbon sheets should fall short of the leading edges of the forms and with said leading edges coincident. The platen may now be raised again, the forms straightened, and, by holding the forms but not the carbon sheets, the carriage 23a may be moved backwardly against the stop 61.

These operations cause the leading edges of the carbon sheets to assume the same positions in relation to the first set of untyped forms as originally, but the holder 27 has been moved forwardly relative to the carriage an extent equal to the length of carbon sheets removed.

The procedure used in removing the used portions of the carbon sheets must be varied somewhat due to the layout of the forms used and the location of the typed lines. The procedure described above assumes what might be called an ideal condition where the typed lines are quite close together so that the working lengths of the carbon sheets are fairly well exhausted before it is necessary to bring a fresh portion of the carbon sheets into working relation with the forms. In practice this ideal condition seldom will be found, as in statement and invoice work a name and address may be typed on the top portion of the form, with a group of items at the center of the forms, and a total of the items at the bottom. This would exhaust three definite areas of the working portion of the carbon sheets and in most cases would leave relatively large unused areas between the entries or groups of entries. Under such circumstances, it is more economical to remove only short lengths of carbon sheet at a time and adjust the holder 27 forwardly one notch at a time so that the working portions of the carbon sheets are exhausted more uniformly, not only between lines but also between groups of entries.

It may happen that only one or two lines close

together are to be typed near the middle or bottom of a form so that the leading edges of the carbon sheets initially fall quite an appreciable distance short of the leading edges of the forms. 5 In this case the used portions of the carbon sheets need not be removed each time the carbon sheet holder 27 is readjusted to provide fresh working portions but, instead, the exhausted portions of the carbon sheets can be left unsevered until 10 eventually the leading edges of the carbon sheets fall a half inch from the leading edges of the forms and then a relatively large portion of the sheets may be removed at one time.

The method of adjustably mounting the carbon holder on the carbon sheet stripper carriage has the advantage of facilitating the adjustment of the carbon sheets to provide fresh working portions as it requires only a simple operation to adjust the holder and there are no clamping 15 screws or spring catches to loosen or become accidentally disengaged. In spite of the ease with which the holder 27 may be adjusted relative to carriage 23a, the holder is at all times positively locked against accidental displacement.

25 It is desirable that the notches 23d in carriage 23a be so spaced that the distance between any pair of them is never equal to or an exact multiple of the distance the pack of superposed webs with interleaved carbons is spaced by the typewriter line spacing mechanism. Otherwise, when the practice is followed of readjusting the carbon sheet holder 27 only a small amount to more economically use the carbon sheets when only a few items widely line-spaced are printed, partly exhausted areas of the carbon sheets might register 30 exactly with the printing zone on the platen, with the result that some lines might be printed very clear and sharp while other might be so faint as to be unreadable. By making the spacing of notches 23d non-coincident with the line space 35 increments, partly exhausted areas of the carbon sheets will overlap other partly exhausted areas and the carbon sheets will be most economically used.

40 While there has been shown and described and pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

45 What is claimed is as follows:

1. In combination with the frame of a typewriter carriage, a pair of spaced frame extensions, platen supporting members slidably mounted in said extensions; a pair of toggles, each pair connecting one of the platen supporting members with the frame extensions whereby the bending of said toggles moves said members to carry the platen to move from a typing to a non-typing position, stop means to permit the toggles to move beyond a dead center position to thereby lock the platen in typing position, a manually operable member, means actuated by said manually operable member interconnecting the toggles for bending both toggles simultaneously whereby to move the platen to its non-typing position, a stationery tearing knife, a clamping bar cooperating with said knife, and means for concurrently moving the clamping bar away from said knife when said lever is operated to move the platen to its non-typing position.

2. In combination with the frame of a typewriter carriage, a pair of spaced frame extensions, platen members slidably mounted in said extensions; a pair of toggles, each connecting one of the platen supporting members with the frame extensions whereby the bending of said toggles causes the platen to move from a typing to a non-typing position, stop means to permit the toggles to move slightly beyond a dead center position to thereby lock the platen in typing 10 position, a manually operable lever, means actuated by said lever and interconnecting the toggles for bending both toggles simultaneously whereby to move the platen to its non-typing position, a paper bail normally cooperating with 15 the platen in the path of its movement from a typing to a non-typing position, and means to concurrently move the paper bail out of cooperative relation with the platen and out of its path of movement when said lever is actuated to 20 move the platen from typing to non-typing position.

3. In a typewriting machine, a carriage frame, a pair of end plates rigidly mounted in said carriage and extending vertically, a carrier slidably mounted in said end plates for vertical movement, a platen rotatably mounted in said carriage; toggle mechanism interconnecting the carrier and the end plates and operative, when the platen is in its lower or typing position, to lock the 30 platen against movement to its upper or non-typing position; a manual lever for operating the toggle mechanism to raise the platen to permit work-sheets wrapped around the platen to be stretched out flat in a substantially horizontal 35 position to permit carbon sheets interleaved with the work-sheets to be displaced relative to the work-sheets, and detent means for yieldingly retaining the carrier and platen in elevated position.

4. In a typewriting machine, a carriage frame, a pair of upward extensions mounted on said frame, a platen carrier slidably mounted in said extensions for vertical movement, a platen rotatably mounted in said carrier, toggle mechanism 45 interconnecting said carrier with said frame and normally operative to lock the carrier in lowered positions to hold the platen in typing position, a manual lever for operating the toggle mechanism to raise the carrier and the platen to a non-typing 50 position to permit forms wrapped around the platen to be stretched out flat in a substantially horizontal position, a paper bail co-operating with the platen when in its typing position to hold the forms against the platen, and means 55 whereby the movement of the platen to its elevated position moves the paper bail to ineffective position.

5. In a machine of the class described, the combination with the carriage, a rotatable platen movably mounted in the carriage for displacement from a typing position to a non-typing position wherein forms wrapped around the platen may be stretched out flat, a relatively stationary tearing knife, a stationery supporting bar co-operating with the platen, a movable clamping bar co-operating with the knife, means to hold the movable bar in co-operation with said knife when the platen is in its typing position and means responsive to displacement of the platen 70 to non-typing position for moving said movable bar out of co-operation with said knife and moving said stationery supporting bar out of co-operation with the platen.

6. In a fanfold billing machine, a platen, a

platen supporting frame, means to movably mount the platen in said frame whereby the platen may be displaced from a typing to a non-typing position, means to actuate the platen to a non-typing position and including a toggle arranged to lock the platen in typing position, a

tearing knife disposed in front of the platen in its typing position, and a paper clamping bar cooperating with said knife when the platen is in its normal position and movable with the toggle toward and away from said knife.

JOSEPH WILLIAM MILES.
